UNITED STATES PATENT OFFICE

HERMAN GOLDBERG, OF CHICAGO, ILLINOIS, ASSIGNOR TO WOLFF COAL SAVER COMPANY, OF CHICAGO, ILLINOIS, A CORPORATION OF DELAWARE

DRAFT CONDITIONER

Application filed September 11, 1930. Serial No. 481,111.

My invention relates to draft regulating mechanism and one of the objects is the provision of improved and efficient automatic regulating mechanism adapted to operate as 5 a draft conditioner in a heating system.

A further object of the invention is the provision of an improved and efficient draft conditioner and controlling mechanism therefore for effecting the operation thereof whenever the door of the furnace is opened for the 10 purpose of supplying fuel thereto.

Another object of the invention is the provision of automatic means for temporarily opening wide the damper when fuel is first 15 supplied to the furnace and then permitting the damper to move to an intermediate position which it is to occupy during the operation of the furnace.

A further object of the invention is the 20 provision of draft regulating mechanism comprising a damper combined with a retarding device to effect movement of the damper from a wide open position or temporary running position to an intermediate 25 or normal running position.

Another object of the invention is the provision of means for electro-magnetically 30 operating a damper and controlling such operation in unison with the opening and closing of a furnace door of a heating system.

Other objects of the invention will appear 35 hereinafter, the novel features and combinations being set forth in the appended claims.

In the accompanying drawings—

Fig. 1 is an elevational view of my improved electro-magnetic mechanism for operating a damper, parts being shown in position when the damper is substantially 40 closed;

Fig. 2 is an enlarged side elevational view of the electro-magnetic damper operating mechanism, parts being broken away to show details of the interior construction;

Fig. 3 is an elevational view similar to Fig. 1, but with the electro-magnet energized for movement of the damper to its initial or temporarily wide open position;

Fig. 4 is a view similar to Fig. 3 illustrating the position that the parts will take after

the electro-magnet has been energized and the retarding device has permitted the damper to move to its intermediate or normal running position;

Fig. 5 is a perspective view of a furnace 55 with my improvements combined therewith;

Fig. 6 is an enlarged detail view in plan showing the door operated switch control box;

Fig. 7 is an elevational view of the switch 60 control box with the cover removed;

Fig. 8 is a side elevational view at the switch control box with a portion broken away to show the pilot lamp; and

Fig. 9 is a diagrammatic view of the 65 circuits and connections of the control system embodied in the arrangement shown in Fig. 5.

Referring to Figs. 1 and 5 it will be seen that a flue 10 which leads from the furnace 70 11 is provided with a damper 12 which when in its dotted line position shown in Fig. 1 is in its so-called closed position. Fig. 2 being a sectional view taken on the line 2—2 of Fig. 1 shows openings at 13 and 14 75 between the damper 12 and the upper and lower interior walls of the flue 10. Openings may be provided at 15, 15 for ingress of air and travel thereof along narrow chambers in zig zag paths to the interior of the flue 10, 80 but this construction is no part of the present invention.

The upright position of the damper 12 shown in dotted line in Fig. 1 and in elevation in Fig. 2 is the position that the damper 85 occupies when the furnace is banked. The spaces around the damper including those designated 13 and 14 in Fig. 2 are sufficient to afford ample draft when the furnace is banked.

The damper 10 is secured to a rock shaft 16 which is mounted in suitable bearings of the flue 10.

To the rock shaft 16 is secured a lever, one 90 arm 19 of which is provided with an adjustable weight 20 and the other arm 21 of which is provided with a transverse pin 22. The lateral ends of the pin 22 project through slots 23 in the upper end portions of the links 24, 24. The lower ends of the links 24, 24 100

are pivoted at 25, 25 to the upper end of the plunger 26 which extends downwardly into the solenoid 27.

The upward movement of the arm 21 and the upward movement of the plunger 26 are limited by one of the links 24 striking at its upper end against the stop screw 28. The latter is adjustable relatively to the stationary bracket 29 and may be secured in adjusted position by means of the lock nuts 30, 30.

A detachable casing 31 entirely encloses the solenoid 27, the plunger 26, the links 24 and the arm 21, but the arm 19 projects through a slot in the left hand portion of the casing 31 and this slot permits sufficient freedom of movement of the arm 19 to enable it to move from its position shown in Fig. 1 to its position shown in Fig. 3.

The upper end of said slot is illustrated by a dotted line at 32 in Fig. 1. Such upper end may be relied on to prevent movement of the arm 19 to a position where the pin 22 will be in alinement with the pivots 16 and 25. Such limiting position is shown in Fig. 3.

When the electro-magnet comprising the solenoid 27 and the plunger 26 is energized the rapid downward movement of the plunger 26 from the position shown in Fig. 1 will cause the parts to assume the position shown in Fig. 3. The momentum of the weight 20 will be sufficient to throw the arm 19 to its uppermost position against the upper limit 32 of the slot in the upper left hand portion of the casing 31. When the solenoid 27 is first energized the pin 22 is engaged by the upper ends of the slots 23 and such engagement continues while the plunger 21 is moving downwardly and until such plunger reaches the lower limit of its stroke shown in Fig. 3, whereupon the momentum of the weight 20 will cause the pin 22 to ride along the slots 23 until such pin is at the lower ends of these slots as shown in Fig. 3 or until the arm 19 strikes against the stop 32. If desired, the arm 19 may strike against the stop 32 before the pin 22 reaches the bottoms of the slots 23.

When the door of the furnace is opened as hereinafter more fully described, the solenoid 27 is energized and the damper 12 is moved to its wide open position or horizontal position as shown in Fig. 3, which is the temporary running position. This movement is effected by the energization of the electro-magnet and the consequent momentum exerted by the weight 20.

After the positions of the parts shown in Fig. 3 have been attained it is desirable that the weight 20 should move downwardly with a retarded movement, so that the damper 12 during operation of the furnace will occupy the position shown in Fig. 4, which position is the normal running position.

As shown in Fig. 2 friction discs 33, 33,

preferably of fibrous material, are mounted on the end portions of the pin 22 between the lateral ends of the arm 21 and the upper ends of the links 24. A bolt 34 extends freely through openings in the links 24 and its screw threaded end is provided with a compression spring 35. Two nuts 36, 37 are mounted on a screw threaded end of the bolt 34 and the head 38 of the bolt acts as an abutment. It will thus be seen that the spring 35 presses the links 24 toward each other and against the friction discs 33. The pin 22 extends through perforations in the centers of the friction discs 33.

When the electro-magnet is energized, its plunger 26 is suddenly pulled down and the weight 20 consequently flies quickly to its uppermost position shown in Fig. 3. The weight 20 then starts to descend, but this movement is retarded by the reason of the braking action afforded by the friction discs and the spring pressed links 24 associated therewith. The damper 12 will therefore move slowly from its horizontal or wide open position shown in Fig. 3 to its slanting or normal running position shown in Fig. 4. During this movement of the damper from its temporary running position to its normal running position, the furnace door is opened for the purpose of manually supplying fuel to the furnace. By means of the nuts 36 and 37 the retarding action on the damper may be regulated so that by the time that a fireman is through supplying fresh fuel to the furnace the damper will be in its normal running position shown in Fig. 4 when the fireman closes the furnace door.

Such manual replenishment of fuel in a furnace is intermittent and it is desired to effect the operation of the draft conditioner automatically in unison with the opening and closing of the furnace door. I have therefore provided switch mechanism which will be automatically operated in accordance with the position of the furnace door.

As shown in Fig. 5 a switch box 39 is secured to the front of the furnace and is provided with a reciprocating rod 40 which projects from the lower left hand portion of the switch box so as to be in position to be engaged by the arm 41 which is secured to the furnace door 42 near the hinge axis 43 thereof. When the door 42 is closed the arm 41 moves on the vertical axis 43 in a clockwise direction and by engaging the outer end of the rod 40 pushes the latter toward the right against the action of the spring 44 in the switch box.

The rod 40 is connected at 45 to an upright lever 46, the lower end of which is pivoted at 47 to the bottom of the switch box.

The upper end of the lever 46 has a pin and slot connection at 48 with a mercury switch which is pivoted at 49 to the rear wall of the switch box.

Fig. 9 is a wiring diagram of the circuits and connections for the switch box and the electro-magnet which operates the damper 12. The main line switch 50 is adapted to connect the supply mains 51 to the conductors 52 and 53. The main line switch 50 may be a snap switch operable by means of a lever 54 projecting through the cover 55 of the switch box 39. The conductor 53 is connected to one terminal of the mercury switch 56, the other terminal of which is connected to the conductor 57. By means of connector screws 58 and 59 on the terminal block 60, composed of insulating material, the conductor 57 may be connected to the conductors 61 and 62 which are connected to the pilot incandescent lamp 63. The terminals 58 and 59 may be respectively connected to the terminals 64 and 65 which, in turn, are connected to the conductors 66 and 67 leading to the terminals of the solenoid 27.

The mercury switch 56 is in its closed position when tilted as shown in Fig. 7 in full lines. This corresponds to the open position of the furnace door 42. When the latter is closed the arm 41 pushes the rod 40 toward the right against the action of the spring 44, whereupon the lever 46 and the mercury switch 56 will be moved to their dotted line positions shown in Fig. 7, thereby opening the mercury switch.

In Fig. 9 the main line switch 50 and the mercury switch 56 are both shown in their open position. The plunger 26 will then be in its uppermost position and the damper 12 will be in its banked position. If the main line switch 50 is closed while the furnace door is closed, the mercury switch 56, being in the return conductor 53, will keep both the solenoid and the lamp 63 cut off from the supply mains 51. The lamp 63 is in parallel with the solenoid 27. Therefore, as soon as the furnace door is opened and the spring 44 acts to close the mercury switch 56, the pilot lamp 63 will be lighted up and this may be observed through the pilot window 68 in the upper end of the cover 55 of the switch box. The energization of the electro-magnet of the draft conditioner shown in Figs. 1, 3 and 4 will move the damper from the position shown in Fig. 1 to the position shown in Fig. 3 after which the retarding mechanism permits the weight 20 to move the damper to the normal running position shown in Fig. 4.

Independently of the draft conditioner, the furnace attendant may move the check door 69 in one side of the flue 10 to various positions on its hinge 70 by means of the chain or draft connection 71 which is trained over pulleys 72, 73 to a stationary anchorage 74 when the check door 69 is closed. For holding the check door 69 in various positions the free end of the chain 71 may be connected to the anchorages 75, 76, 77 and 78 which are located at various elevations.

It is also desirable to operate the damper 12 manually to various positions in accordance with the weather conditions. For this purpose a chain 79 is connected to the weight arm 19 as shown in Fig. 5 and trained over pulleys 80, 81 and connected at 82 to the extension 83, preferably consisting of a flexible metal cable, the lower end of which is connected to the pulley 84 at 85 and wound around such pulley.

The pulley 84 is secured to a rock shaft 86 which is mounted in bearings 87 and 88 in the switch box 39. Secured to the outer end of the rock shaft 86 is an operating lever 89 which is provided with an extension arm 90 having a pin 91 adapted to fit into any one of the four openings 92, 93, 94 and 95 in the right hand outer side of the switch box. The inner end of the rock shaft 86 is provided with a collar 96 between which and the bearing 87 is located a compression spring 97. This spring tends to move the pin 91 into one of the openings 92, 93, 94 or 95 when the lever 89 is released.

When the lever 89 is swung in an anti-clockwise direction, as viewed in Fig. 8, the pulley 84 will be moved correspondingly and this operation slackens the cable 83 and the chain 79 and therefore permits the weight 20 to move the damper 12 to its banked position as shown in Fig. 1. The arrangement is such that the damper 12 is free to move to its banked position when the pin 91 is in the recess 92 shown in Fig. 8.

By moving the lever 89 from its banked position, so that the pin 91 rests in the recess 93, the pulley 84 will be moved clockwise to exert a pull on the chain 79 and thereby lift the weight 20 to move the damper to a partially open position corresponding to that desired for mild weather. When the weather is cold and an increased draft is desired, the pin 91 may be moved so that it will rest in the recess 94 marked "Cold". This movement of the lever 89 will move the damper 12 to a more open position.

By moving the lever 89 to its full line position shown in Fig. 8 where the pin 91 will rest in the recess 95, the damper may be moved to any desired position, depending upon the predetermined connections between the pulley 84 and the weight arm 19. For instance, the index 92 may be for setting the damper in the position shown in Fig. 1; that is, the banked position. The index 93 may be for setting the damper in a position intermediate that shown in Fig. 1 and that shown in Fig. 3. The index 94 may be for setting the damper in the position shown in Fig. 4 corresponding to the normal running position. When the weather is extremely cold the damper may be set to its widest open position shown in Fig. 3.

It should be particularly noted that when the manually operated mechanism between

the switch box and the damper is used to set the damper in its various positions at 92, 93 and 94 there will be no interference with the electro-magnetic mechanism and the automatic operation thereof to move the damper to its wide open position whenever the furnace door is opened. This is because the chain 79 is connected to the upper side of the weight arm 19 at 98 and, consequently, when 10 the solenoid 27 is energized to pull down the plunger 26, the upward movement of the weight arm 19 will merely cause temporary slack in the chain 79. The retarding mechanism will also operate automatically to permit 15 the weight 20 to move the damper back to its running position.

Obviously those skilled in the art may make various changes in the details and arrangement of parts without departing from 20 the spirit and scope of the invention as defined by the claims hereto appended and I wish therefore not to be restricted to the precise construction herein disclosed.

Having thus shown and described an embodiment 25 of my invention what I desire to have protected by Letters Patent of the United States is:—

1. In a draft conditioner, the combination with a damper, of electro-magnetic mechanism for operating the same, a control box, a lever, a rock shaft connected to said lever and pivotally mounted in said box, means for holding 30 said lever in any one of a plurality of set positions, a member secured to said rock shaft, a cable having one end connected to said member and the other end to said damper to serve as a draft connection between said lever and said damper to enable said damper to be set in any one of a plurality of positions corresponding to the set 35 positions of said lever, a mercury switch in said box, a spring-pressed push-rod connected to said mercury switch and extending to a position outside of said box, a manually operable switch in said box, a pilot light in said box, a window for said pilot light, and circuits and connections for effecting energization of said electro-magnetic mechanism to open the damper when said manual switch 40 is closed and said spring-pressed push-rod is operated to close said mercury switch.

2. In a draft conditioner, the combination with a damper, of an electro-magnet comprising a solenoid and a plunger, and connections 45 between said plunger and said damper to effect movement of the damper to wide open position when the solenoid is first energized followed by movement of the damper to an intermediate position while the solenoid remains energized.

3. In a draft conditioner, the combination with a damper, of an electro-magnet comprising a solenoid and a plunger, and means comprising a pin and slot connection between 50 said plunger and said damper to effect initial

movement of the damper to wide open position followed by movement thereof to an intermediate position after said solenoid has been energized.

4. In a draft conditioner, the combination 70 with a damper, of electro-magnet mechanism comprising a solenoid and a plunger, a link pivoted to said plunger, and means comprising a pin and slot connection between said link and said damper for effecting initial 75 movement of the latter to wide open position followed by movement thereof to an intermediate position after said solenoid is energized.

5. In a draft conditioner, the combination 80 with a damper, of electro-magnet mechanism, means comprising a pin and slot connection between said damper and said electro-magnetic mechanism to permit movement of said damper to wide open position when said electro-magnetic mechanism is energized, and returning means associated with said pin and slot connection to effect a timed movement 85 of said damper from wide open position to an intermediate position.

6. In a draft conditioner, the combination with a damper, of electro-magnetic mechanism comprising an armature, spaced-apart plates each pivoted at one end of said armature and each having a slot in its other end, an actuating arm connected to said damper, a pin carried by said actuating arm and extending into said slots, friction discs at the sides of said arm in engagement with the adjacent faces of said plates, and resilient 100 means for pressing said slotted ends of said plates against said friction discs.

7. In a draft conditioner, the combination with a damper, of a weighted arm connected thereto, an actuator, means comprising a lost motion connection between said actuator and said weighted arm to permit the latter to move the damper to wide open position after operation of said actuator, and a spring-pressed friction device associated with said 105 pin and slot connection to effect retarded movement of said damper from its wide open position to a predetermined intermediate position.

In testimony whereof I have signed my 110 name to this specification on this 8th day of September, A. D. 1930.

HERMAN GOLDBERG.
